CLAIM

We claim the ornamental design for a flag door handle cover,
as shown and described.

DESCRIPTION

FIG. 1 is a top plan view of the flag door handle cover,
showing our new design;

FIG. 2 is a side view thereof;

FIG. 3 is the opposite side view thereof;

FIG. 4 is an end view thereof;

FIG. 5 is the opposite end view thereof; and,

FIG. 6 is a bottom plan view thereof.
